I. J. POTTER

SHOULDER STRAP HOLDER

Filed April 19, 1924

UNITED STATES PATENT OFFICE.

ISABELLE JOHNSTON POTTER, OF BIRMINGHAM, ENGLAND.

SHOULDER-STRAP HOLDER.

Application filed April 19, 1924. Serial No. 707,644.

To all whom it may concern:

Be it known that I, ISABELLE JOHNSTON POTTER, residing at Birmingham, England, a British subject, have invented certain new and useful Improvements in Shoulder-Strap Holders, of which the following is a specification.

This invention is for improvements in or relating to devices for holding the shoulder straps of underclothing in position, and has for its object the provision of a device of the above character wherein the shoulder straps are gripped together and held in position relatively to an outer garment so as to prevent the same from slipping over the end of the shoulder.

The invention is more particularly described with reference to the accompanying drawings, in which:—

Fig. 1 shows in perspective one method of carrying the invention into effect;

Fig. 2 is a top view of the device illustrated in Figure 1;

Fig. 3 is a modification of the device illustrated in Figure 1;

Figs. 4, 5, 6, 7, 8, 9 and 10 illustrate one method of building up a device of this character.

Referring to Figs. 4-10, there is illustrated in sections, one method of building up a device which constitutes the subject-matter of the present invention. A length of strip metal *a* is cut to a certain predetermined length, and is provided with a sharpened portion *b* at one end thereof, which portion forms the point of a safety-pin. The strip metal *a* is first bent so as to provide a loop *c* at the end thereof which is remote from the point *b*, as illustrated in Figure 3. The strip of metal is then bent at a point along its length so as to form a portion *d* adjacent to the loop *c* at right angles to the remaining length of the strip metal element *a*.

The bend between the limb *d* and the remaining portion of the element *a* is substantially as illustrated at *m*, thus ensuring, when the device is built up, that shoulder straps may be easily inserted in the clip.

The portion *d* is then bent parallel to the remaining portion of the length of strip metal, and a right-angle bend is then made in the portion of the strip metal so as to situate the loop *c* at the mid-point of a length *e*, with the portions *d* and *e* parallel to one another, and the loop *c* facing to-

wards the limb *e*. The remaining length of the strip metal is then bent parallel to the portion *e* so as to lie adjacent to the portion *d* and form a limb *f*, and a right-angle bend is then made in the remaining portion. The free end of the strip metal is then bent downwardly and forwardly, and then backwardly and upwardly, with a kink *g* at its free end to form a loop *l*, and the free end is carried parallel to and adjacent with the limb *f* to form a limb *h*, whereupon it is either bent back upon itself so as to form a pin *k*, or it is first bent into a complete loop, and thereafter bent parallel to the limbs *f* and *h* so as to form the pin of a safety-pin which is adapted to engage with the kink *g* formed in the forward loop *l*, hereinbefore referred to.

It will be found that by constructing a device in the manner hereinbefore described, the limb *d* will lie adjacent to, and between, the limbs *f* and *h* so that if the safety-pin is secured in position upon an outer garment, and a number of shoulder straps are pressed between the limb *d* and the limbs *f* and *h* until the same pass into the space between the limb *e* and the limbs *d*, *f*, and *h*, the same will be held firmly therein, and prevented from slipping over the edge of the shoulder.

Due to the loop *c*, it will be observed that when it is required to withdraw the shoulder straps from the said clip, the edges of the same have only to be inserted under the edge of the loop *c*, whereupon they may be sprung out of the clip, when desired.

It is to be understood that although the mode of operation hereinbefore set forth particularly describes the mode of construction as commencing with the end of the strip metal which is remote from the sharpened end thereof, nevertheless, the operation could be started from the sharpened end of the pin and worked backwardly in the reverse direction. By carrying out the steps hereinbefore set forth, a pin such as illustrated in Figs. 1 or 3 will be formed, and it will be found that the same constitutes a very simple and efficient means for securing the shoulder straps of underclothing in position relatively to an outer garment, and prevents the same from slipping over the shoulder.

The device hereinbefore described is simple in its construction, efficient in its operation, and inexpensive in its manufacture,

and has the advantage over clips which merely hold the shoulder straps together, inasmuch as it ensures that the shoulder straps are held in a definite position relatively to an outer garment, and by so doing obviates the possibility of the shoulder straps as a whole slipping over the edge of the shoulder.

What I claim is:

- 10 1. A garment holding device comprising means for detachably connecting it to an outer garment at the shoulder of the wearer and a clip comprising a loop into and out of which a shoulder strap may be moved, the passage into and out of the loop having a yieldable obstruction that terminates within the confines of the loop and above the strap-supporting portion of the loop, the terminal of said obstruction extending 15 toward such strap-supporting portion of the loop and free therefrom, whereby the strap lies between such terminal and said strap-supporting portion of the loop.
- 15 2. A garment holding device comprising means for detachably connecting it to an outer garment at the shoulder of the wearer and a clip comprising a loop into and out of which a shoulder strap may be moved, the passage into and out of the loop having a yieldable obstruction, that terminates in 20 a rounded end within the confines of the loop the shoulder strap supporting portion of the loop being below said obstruction, the terminal of said obstruction extending

35 toward such strap-supporting portion of the loop and free therefrom, whereby the strap lies between such terminal and said strap-supporting portion of the loop.

3. A garment holding device comprising a safety pin and a loop to receive a garment strap with upper and lower sides parallel with the length of the safety pin the passage into and out of the loop being between the safety pin and the loop side adjacent thereto the lower side being the strap-supporting member and the upper side terminating midway between the loop ends.

4. A garment holding device comprising a safety pin and a loop to receive a garment strap with upper and lower sides parallel 40 with the length of the safety pin the passage into and out of the loop being between the safety pin and the loop side adjacent thereto, said loop side terminating in a rounded end within the confines of the loop 45 the lower side being the strap-supporting member.

5. A garment holding device comprising a safety pin and a loop parallel with the safety pin having a movable side adjacent 50 the side of the safety pin, the safety pin and loop being formed from a single piece of strip metal one end of said strip being pointed and the other end rounded and situated within the confines of said loop.

In testimony whereof I hereunto affix my signature.

ISABELLE JOHNSTON POTTER.
